United States Patent Office.

EDMUND H. EBERMAN, OF LAMPETER SQUARE, PENNSYLVANIA.

Letters Patent No. 74,900, dated February 25, 1868.

IMPROVED RAILROAD RAIL-JOINT SPLICE.

The Schedule referred to in these Letters Patent and making part of the same.

TO ALL WHOM IT MAY CONCERN:

Be it known that I, EDMUND H. EBERMAN, of Lampeter Square, in the county of Lancaster, and State of Pennsylvania, have invented a new and improved Mode to Secure the Joining of Rails on Railroads; and I do hereby declare that the following is a full and exact description thereof, reference being had to the accompanying drawings, making a part of this specification, in which—

Figure 1 shows a perspective view of a joint secured by my device.

Figure 2 the same, with joining removed, to show the formation of the double dove-tailed opening between the abutting ends of two rails.

Figure 3, one end shown separated.

Figures 4, front view of two adjoining rails, with the two flanged and double dove-tailed solid plugs B B', the headed bolt C, with the screw-nut D detached, showing the outer and inner face of said plugs B.

Figure 5 shows the same, applied by a long screw-holt or rod to unite rails across the track on curves to prevent lateral pressure.

Figure 6, a section, showing the two plugs to meet centrally in the rail, and the bolt and nut in place.

The nature of my invention is to provide a means of uniting two abutting rails or iron beams, so as to bind in every direction, and supplying a solid, compact filling to the portion cut away. The drawings are so full as to clearly show my invention, and to enable any one skilled in the art to make and use the same it is only necessary to say, that by means of a die the dove-tail slot can be cut out of the ends of each rail, as shown, the plugs being of one size and configuration. When both sides of the rail have the same curve that they can also be made by machinery, and when properly constructed, and the ends of the rails cut, it is only necessary to insert one from each side; they will fill up, each half way, the double dove-tailed opening (fig. 4) made by the union of two rails. B, the outer flange, convex on the inner face, to closely fit up to the sides of the concave rail. b, the double dove-tailed filling. Both plugs B B' are bolted together by a stout-headed screw-bolt, C, and secured and firmly drawn together by the nut D, as shown by fig. 6. The nature of this union is such that it combines the two rails as if in one continuous piece, prevents yielding by its adaptation to resist, in every possible direction, all strain upon the joint, and applicable to secure iron joints on bridges, buildings, &c. I am not aware that a connecting-plug, with a flange, B, straight on the outer face, and double dove-tail b of one uniform piece, perforated for a bolt, was ever employed to secure the joining of rails or other iron bars.

What I claim as my invention, and desire to secure by Letters Patent, is—

The construction of the flanged and double dove-tailed brace and filling or plugs B B', b b', used jointly or severally, in combination with the bolt C and nut D and dove-tailed slot a cut in the rail, all arranged in the manner shown for the purpose specified.
